UNITED STATES PATENT OFFICE

2,455,549

SPRING WINDING MACHINE

Allen Benjamin, Chicago, Ill.

Application January 5, 1946, Serial No. 639,195

10 Claims. (Cl. 153—64)

1

The invention relates to improvements in the method of and apparatus for winding substantially flat coiled expansible ribbon.

Coiled expansible ribbon of the kind fashioned by the apparatus of the present invention is particularly adapted for use as a wrist band or bracelet. Such wrist bands or bracelets are of a character that will snugly embrace the wrist while being readily expansible so as to facilitate its being slipped over the hand of the wearer. Heretofore wrist bands of this general character have been fashioned from a plurality of interconnected links usually associated one with the other in a lazy-tong organization. Such structures invariably involve costly manufacturing processes and further, are not entirely satisfactory in use because of the likelihood of the link structure coming apart should the various portions thereof become worn or broken. The apparatus of the present invention is particularly designed to provide an endless one piece expansible coiled spring ribbon in a simple and efficient manner, thereby producing at low cost a bracelet or wrist band suitable for all of the uses for which the hereinabove described link structures are used.

It is, therefore, an object of the present invention to provide an apparatus for producing expansible wrist bands from a single strand of shape retaining material such as steel wire, or the like.

Another object of the invention is to provide an improved method whereby a strand of shape retaining material may be easily and quickly fashioned into an expansible coiled spring ribbon.

When a strand of stiff shape-retaining material is wound upon a mandrel, tightly, to form a coil, the inherent resiliency in the strand causes the coils to spring back when the pressure means is removed. It is, therefore, another object of the present invention to provide an apparatus for winding a strand into a coil which embodies means to set the strand forming each coil ahead of the normal spring-back position so that the peripheries of the coils lie in a common plane.

It is preferred that a coiled expansible flat ribbon of the kind mentioned hereinabove and useful as a wrist band, be fashioned in such manner that the opposed faces thereof be concaved slightly throughout its length to minimize the surface contact upon the wrist of the wearer and further to enhance its general appearance. It is, therefore, another object of the present invention to provide a method of and apparatus for shaping the opposed faces of the expansible ribbon so as to provide the desirable concave faces thereon.

Another object of the present invention is to provide an apparatus of the kind referred to herein which is not expensive to manufacture,

2

but which is easy to operate and highly efficient in use.

Other and further objects of the present invention will be apparent from the following description and claims and are illustrated in the accompanying drawings which illustrate a preferred embodiment and the principle thereof and which is considered to be the best mode contemplated for applying that principle. Other embodiments of the invention embodying the same or equivalent principle may be used and structural changes may be made as desired by those skilled in the art without departing from the spirit of the invention and the purview of the appended claims.

In the drawings:

Fig. 1 is a front elevational view of the apparatus showing the parts in one position of its operation cycle.

Fig. 1A is a vertical side elevational view of the setting cam showing a portion of the arbor associated therewith.

Fig. 2 is a top plan view of the apparatus.

Fig. 3 is a perspective view of a fragment of coiled expansible ribbon of the kind fashioned on the present apparatus.

Fig. 4 is an enlarged fragmentary detail elevational view of the arbor and its associated elements, illustrated in a position substantially like that shown in Fig. 1.

Fig. 5 is a fragmentary radial sectional view through the periphery of the feed wheel.

Fig. 6 is a fragmentary detail radial sectional view through the periphery of the setting cam.

Fig. 7 is an enlarged fragmentary elevational view, similar to Fig. 4, but showing the arbor in a position assumed prior to being rotated 90° into the position shown in Fig. 4.

Fig. 8 is a horizontal sectional view taken substantially on line 8—8 of Fig. 7.

Fig. 9 is a view similar to Fig. 7 but showing the arbor rotated approximately 130° out of the position in which it is shown in Fig. 7.

Fig. 10 is a horizontal sectional view taken substantially on line 10—10 of Fig. 9.

Fig. 11 is a view similar to Fig. 9 but showing the arbor advanced approximately 115° beyond the position in which it is shown in Fig. 9.

Fig. 12 is a horizontal sectional view taken substantially on line 12—12 of Fig. 11.

Fig. 13 is a sectional view of the bending roll, showing the strand in place.

Fig. 14 is a fragmentary enlarged plan view of the bending roll, with the strand in place thereon.

Referring particularly to the exemplary apparatus as illustrated in Figs. 1 and 2, said apparatus is supported by a vertically disposed substantially heavy plate 11 firmly secured to a base 12

in any suitable manner. The plate 11 has a suitable bearing boss 13 therein located inwardly of the edges thereof to provide a bearing for a horizontal stud shaft 14 which extends through to the front side of the plate 11 and carries, firmly secured thereon, an arbor 15. The arbor 15 is perhaps best shown in Fig. 4 and it includes a circular body portion 16 having a pair of diametrically aligned eccentric pins 17 and 18 projecting outwardly in the same direction from one face thereof. The pins 17 and 18 are spaced equal distances from the axial center of the body 16 so that when the body 16 is rotated about its axis, the pins 17 and 18 will describe a concentric circle about said axis.

The end of the stud shaft 14 extending beyond the back face of the plate 11 has, firmly secured thereon, a drive wheel 19 which in the present instance may comprise a pulley adapted to have a driven connection as by means of a belt or the like with a suitable source of power, not shown. It should be evident that when the power source is in operation, the pulley 19 is driven at a constant rate of speed so as to impart rotation at a uniform rate of speed to the arbor 15.

The eccentric pins 17 and 18 constituting a part of the arbor 15 provide in effect a diametrically elongated mandrel around which a strand of shape-retaining material, such as steel wire, suitably tempered, is adapted to be continuously wound so as to fashion a relatively wide substantially flat coiled expansible ribbon which, when cut into desired lengths, is utilized for fashioning wrist bands and bracelets of the kind referred to hereinbefore. The wire strand, indicated at 21, is fed to the apparatus through a tension member 22 preferably carried adjacent the upper edge of the plate 11 and which may consist of a bracket 23 firmly secured to said plate having an adjustable block 24 therein carried on the end of an adjusting screw 25 which may be manipulated readily to increase or decrease the tension on the wire strand 21 which is guided between the block 24 and member 23, as shown. The tensioned wire strand 21 is guided over a bending roll 26 mounted for free rotation upon a stud screw 27 firmly secured to the plate 11, from where it is carried downwardly for engagement with the arbor 15.

The bending roll 26 is best illustrated in Figs. 13 and 14 and it is provided with a peripheral groove 26a of a width greater than the diameter of the strand 21 which is fed into the groove at the upper periphery thereof and then carried around said roll, as shown, so that the strand portion leading off of said roll partially underlies a portion of the previously laid strand portion before being led therefrom. This limited overlapping of the strand portions in the peripheral groove tends to provide rolling frictional resistance to feeding of the strand whereby the strand is maintained under a constant uniform tension at all times during machine operation.

Upon initiating a winding operation, the end of the wire strand leading from the bending roll 26 is attached, as by being wrapped partially around or otherwise connected to one of the pins 17 or 18, so that when the arbor is rotated, the wire is carried successively around a pair of pins 17 and 18. This winding of the wire about the pins 17 and 18 will produce loops of wire that are substantially elongated planularly. A ribbon fashioned from such loops is, however, unsuited for use as a wrist band or the like because of its unattractive flat appearance; and further, such

a ribbon would be objectionable unless means is provided to cooperate with the arbor to insure tight uniform winding of the strand therearound, without spring-back, it being evident that the inherent stiffness of the wire strand would be such as to cause the longitudinal reaches of the elongated loops to bow outwardly midway between the pins 17 and 18, as well as to cause the loops leaving the arbor to spring back irregular distances sufficiently to result in an irregular surface in the finished ribbon. Accordingly, means is provided in the form of tensioning and setting elements to coact with the arbor to maintain the wire strand and selected loops under sufficient tension at all times to prevent outward bowing of the longitudinal reaches of said loops and further, to set the completed loops so that the finished ribbon has a smooth surface.

One of such tensioning elements is provided in the form of a feed roller or former 28 which is mounted for free rotation upon a stud 29 carried on the upper end of one arm 31 constituting a part of a bell-crank 32. The bell-crank 32 is pivoted as by a stud screw 33 to the front face of the vertical plate 11. The other arm 34 of the bell-crank 32 has a slotted aperture 35 adjacent its free end, through which a guide rod 36 freely extends. The rod 36 preferably is threaded on its lowermost end to receive an adjusting nut 37 and said rod extends upwardly through a horizontally disposed portion 38 of an arm 39 which may be formed integral with the vertical plate 11. The uppermost end of the rod 36 also preferably is threaded to receive a stop nut 41. A tension spring 42 is fitted around the rod 36 during the assembly of said rod, which spring normally tends to urge the arm 34 of the bell-crank 32 downwardly so as to rock the bell-crank in a clock-wise direction about its pivot 33 to thereby maintain the feed roller 28 tightly against the eccentric pins 17 and 18 or, more properly, against any wire strand interposed between said roller and said pins. The nuts 37 and 41, or other suitable means, on the ends of the rod 36 hold the rod in place and an adjustable stop 40 carried on the stationary plate 11 provides means whereby the extreme limits of clockwise rotation of the bell-crank 32 may be varied to suit various requirements of use.

The feed roller 28 is of a width substantially equal to twice the diameter of the wire strand 21 and, as is best shown in Fig. 5, it is formed on its periphery with spaced apart shallow peripheral grooves 43 and 44, which grooves are formed on a radius equal to the radius of the wire strand 21. The feed roller 28 is so positioned with relation to the arbor 15 that its rearmost face lies in a plane slightly in advance of the plane of the front face of the arbor body 16. The wire strand 21 being fed to the arbor is received in and guided by the peripheral groove 43 so that said wire is fed to the arbor 15 in close proximity to the front face of the arbor body 16.

A setting cam 45 also is provided to coact with the arbor 15. This setting cam 45 is of substantially the same diameter as the feed roller 28 and it is carried on a stud 46 projecting rearwardly from the upper end of an arm 47 which is pivoted as at 48 to the front face of the vertical plate 11. The arm 47 has a depending leg portion 49 suitably apertured at its lower end to receive therethrough one end of a guide rod 51, the other end of which is slidably guided in a rigid arm 52 extending laterally from one edge of the vertical plate 11. A tension spring 53 is fitted

around the rod 11 during assembly and this spring normally urges the depending leg portion 49 of the arm 47 in a counter-clockwise direction so as to urge the setting cam 45 on the arm 47 in the direction of the arbor 15. A stop 54 is provided to limit counter-clockwise rotation of the arm 47.

The setting cam 45 is formed on its periphery with a peripheral groove 55 having a radius substantially equal to the radius of the wire strand. One side wall of the peripheral groove 55 is however, cut away on a lesser diameter than the greatest diameter of the setting cam so as to provide a shoulder 56 offset inwardly from the opposed shoulder 57 for purposes to be explained hereinafter. The setting cam 45 also is inclined slightly out of the plane of the arbor 15. As best shown in Fig. 1A the setting cam is tilted in such manner that the upper peripheral edge thereof is slightly further away from the plate 11 than is the lower peripheral edge thereof and the peripheral edge thereof overlying the arbor face is more closely spaced to the face of the arbor than is the diametrically opposite peripheral edge. The purpose of the particular peripheral formation of the setting cam and the tilting thereof out of the vertical and transverse planes will be more readily understood following a step by step description of the winding of a plurality of loops on the arbor 15.

Winding of the strand about the arbor 15 can be best described by reference to the developed steps illustrated in Figs. 4 and 6 through 12. Referring particularly to Figs. 7 and 8, the arbor 15 is shown, in a position of rotation with the eccentric pins 17 and 18 located in a substantially horizontal plane, the strand of wire having been initially wound thereon to provide one complete loop. It will be noted upon referring to Fig. 8, that the lead-in portion 21a of the wire strand is guided around the pin 18 in the peripheral groove 43 of the feed roller 28 and that the previously wound strand portion 21b is guided in the companion peripheral groove 44. The wire strand portion 21c extending around the pin 17 lies to the rear of the setting cam 45.

Continued rotation of the arbor in a counter-clockwise direction through one-fourth of a revolution carries the pins 17 and 18 from the horizontally aligned position shown in Fig. 7 into the vertically aligned position shown in Fig. 4. As a result, the feed roller 28 and setting cam 45 have moved inwardly towards each other. When the roller and cam are in this position the lead-in strand reach which is now laid against both pins 17 and 18, in back of strand portion 21d, is bowed inwardly on a radius corresponding to the radius of the feed roller. Inasmuch as the wire strand 21 is shape-retaining, the reach laid in back of the strand portion 21d will retain its bowed position after the roller 28 has been carried outwardly out of pressing engagement therewith. Such outward movement of the feed roller 28, and likewise of the setting cam 45, is illustrated in Fig. 9 wherein the arbor is shown to have advanced counter-clockwise sufficiently to carry the pins 17 and 18 out of vertical alignment.

The wire strand continues to be wound upon the pins 17 and 18, during arbor rotation, under the constant tension imparted by the feed roller 28 and setting cam 45. However, during rotation of the arbor from the position shown in Fig. 7 into the position shown in Fig. 4, the lead-in strand 21a always is laid in between the last formed loop and the face of the arbor body 16.

Sufficient clearance between the wound strand and the arbor face to admit the lead-in strand portion is assured, in the present instance, by a stripper cam 58 located to overlie the face of the arbor 15. As shown, the stripper cam lies close to the arbor face and has its feathered peripheral edge disposed in close proximity to the circle described by the pins 17-18 during arbor rotation. As a result, each time a pin 17 or 18 is carried past the region of the stripper cam, as when the arbor moves from the position shown in Fig. 7 into the position shown in Fig. 4, the strand portion on said pin is cammed outwardly along the pin a distance corresponding substantially to the diameter of the wire strand. Thus, it will be observed that prior to the arbor reaching the position shown in Fig. 4 the strand portion 21c extending around the pin 17 will have been moved outwardly along said pin into such position that it aligns with and engages in the second peripheral groove 44 of the feed roller. Since the strand portion 21b of the initially formed loop rested in the groove 44 of the feed roller, said portion 21b now registers with and engages in peripheral groove 55 on the tilted setting cam 45 so that said portion 21b will ride in said groove 55 while the arbor is moving from the position shown in Fig. 4 through the position illustrated in Fig. 9. Such engagement of the wound strand portions 21c and 21b with the respective peripheral grooves is maintained while the arbor continues to rotate from the position illustrated in Fig. 9 until shortly prior to the time the arbor reaches the position shown in Fig. 11.

As mentioned hereinabove, the setting cam 45 is tilted outwardly-upwardly and, as shown best in Fig. 4, the peripheral groove 55 therein is angularly disposed with relation to the face of the arbor. This angular disposition of the groove results in the strand portion engaged therein being shifted outwardly towards the end of its pin during arbor rotation from the position shown in Fig. 4 to just prior to reaching the Fig. 11 position.

The outward inclination of the setting cam 45 is such that just prior to the arbor reaching the position shown in Fig. 11, the uppermost part of the strand portion 21d riding in the peripheral groove 55 is carried beyond the end of the pin 18, whereupon the tension applied to move the setting cam in a counter-clockwise direction causes said setting cam to move past the end face of the pin 18 (as shown in Fig. 11) carrying the strand portion 21d therewith. This inward movement of the setting cam 45 sets the strand portion 21d ahead of the spring-back position and as the arbor continues to rotate in its counter-clockwise direction, the setting cam is prevented from continued movement in its counter-clockwise direction by its engagement with the strand portion 21c on the pin 17 which had advanced towards the setting cam during arbor rotation. It will thus be observed that the strand portion 21d remains in engagement with the peripheral groove 55 of the setting cam while being set ahead and that as the setting cam is again carried outwardly in a counter-clockwise direction through its bearing contact with the pin 17, said strand portion 21d will spring back into a normal position in substantial alignment with the succeeding loops being formed on the pins 17 and 18. It should be obvious that while the setting cam is acting to set the strand portion 21d ahead of the spring-back, the strand portion of the succeeding loop previously wrapped around the pin

18 is being urged forward along said pin by the stripper cam in the same manner as the strand portion 21c was advanced during the formation of the initial loop. In this manner the successively formed elongated loops are progressively advanced along and finally off of the pins 17 and 18 as said pins are carried through the region of the stripper cam 58 and each loop is set with relation to preceding and following loops so that the finished ribbon has a uniformly flat surface entirely devoid of any irregularities which might result from insufficient or excessive spring-back in any one or more of the loops.

The construction illustrated in the accompanying drawings and described in detail hereinabove contemplates the use of wire stock which may be entirely devoid of any finish of a kind that would lend itself to free substantially frictionless sliding on the pins 17 and 18 during arbor rotation. It is because such wire strands are incapable of being shifted, after having been wound tightly upon the arbor, that the stripper cam 58 is required. In instances where the endless expandable ribbon is fashioned from wire stock such as, for example, wire having a coating of lead or the like thereon, the use of the stripper cam may be eliminated. Such coated wire is readily capable of sliding freely along the pins 17 and 18 in response to force applied on one side thereof as when the lead-in strand portion is being laid into position on the eccentric pins rearwardly of the wound strand.

It is submitted that the exemplary form of the invention shown in the accompanying drawings and described in detail hereinabove is capable of embodying various other modifications in its detail construction and that such variations and modifications may be adopted therein without departing from the spirit of the invention or the scope of the appended claims.

I claim:

1. In an apparatus for winding a substantially flat coil ribbon having concave faces, in combination, a rotatable arbor including spaced eccentrics about both of which a shape-retaining strand is adapted to be progressively wound to produce elongated loops, and yieldable pressure applying means operatively associated with said rotatable arbor and being in continuous engagement with the loops to deform the reaches of said loops extending between the eccentrics inwardly.

2. In an apparatus for winding a stiff strand into a ribbon-like coil spring which includes a mandrel around which the strand is wound to fashion elongated loops, a yieldably mounted cam disposed at an angle to the axis of the mandrel and associated with said mandrel and positioned adjacent the free end thereof for progressively advancing engaged portions of the loops towards the free end of said mandrel and finally urge the advanced portion off of said mandrel, said cam being effective to press the disengaged portion beyond the normal spring-back point of the strand.

3. An apparatus adapted for the manufacture of an expandable ribbon from a shape-retaining strand comprising, in combination, a rotatable arbor having eccentric strand engaging elements, a feed wheel disposed on one side of the arbor axis to guide the strand over said elements during arbor rotation, a setting cam on the opposite side of said arbor axis to receive and guide strand portions wound upon said arbor, independent mountings for said wheel and cam to enable them to move towards and away from the arbor, and

means tensioning said mountings to urge them towards the arbor so that the wheel and cam maintain rolling contact with the strand thereon at all times, at least said wheel being of such a diameter that a peripheral segment thereof substantially bridges the space between the arbor elements when said elements are in vertical alignment so as to displace the strand inwardly on an arc corresponding to the arc of the peripheral segment.

4. An apparatus adapted for the manufacture of an expandable ribbon from a shape-retaining strand comprising, in combination, a rotatable arbor having spaced strand engaging elements, a feed wheel disposed on one side of the arbor axis to guide the strand over said elements during arbor rotation, a setting wheel on the opposite side of said arbor axis to receive and guide strand portions wound upon said arbor, independent mountings for said wheel and cam to enable the wheel and cam to move towards and away from the arbor, means tensioning said mountings to urge them towards the arbor so that the wheel and cam maintain rolling contact with related strand portions at all times, said wheel being of such diameter that a peripheral segment thereof substantially bridges the gap between the arbor elements when said elements are in vertical alignment so as to displace the strand portion bridging said gap inwardly on an arc corresponding to the arc of the peripheral segment, and said setting cam being effective to advance the wound strand off of the arbor and set it ahead of the spring-back point.

5. In an apparatus for winding a wire strand into a ribbon-like coil, an elongated mandrel rotatable about an axis midway between its ends, a feed wheel on one side of said mandrel to guide the wire strand onto said mandrel during rotation, a yieldable mounting for said feed wheel including means to urge the wheel towards the mandrel at all times so as to press the wire strand tightly thereagainst, a setting cam on the other side of the mandrel, and a yieldable mounting for said setting cam including means to urge the said cam towards the mandrel to hold and guide a wound strand portion engaged thereby into a position to free it from said mandrel.

6. In an apparatus for winding a wire strand into a ribbon-like coil, an elongated arbor rotatable about an axis midway between its ends, a feed wheel on one side of the arbor to guide the wire strand onto said arbor during rotation, a yieldable mounting for said feed wheel including means to urge the wheel towards the arbor at all times so as to press the wire strand tightly thereagainst, a setting cam on the other side of the arbor, a yieldable mounting for the setting cam including means to urge said cam towards said arbor to hold the wound wire strand against the arbor, and a stripper associated with the arbor arranged in the path of a strand wound thereon to urge said strand axially along the arbor at predetermined intervals during arbor rotation, said setting cam being effective to successively free wound strands from the arbor.

7. In an apparatus having a rotatable eccentric arbor adapted to have a strand wound therearound to produce a substantially flat ribbon, a yieldably mounted circular setting cam operatively associated with the arbor having its periphery disposed to ride upon one strand of said ribbon during arbor rotation, said setting cam having a peripheral groove to receive said strand, said groove having one of its side walls of

lesser height than its other side wall to enable said one strand to advance into said groove.

8. The herein described method of making a substantially flat expansible ribbon which consists in winding a strand of stiff material around strand engaging elements spaced one on each side of the axis of a rotatable arbor while pressure from an external source is continuously maintained against said strand to hold it to said elements and to bow the reaches of the strand between said elements inwardly thus producing a ribbon having substantially concaved surfaces.

9. In an apparatus for winding a wire strand into a ribbon-like coil, a rotatable arbor including a body having pins extending from one face thereof to form a mandrel, a feed wheel on one side of said mandrel to guide the wire strand onto said mandrel during rotation, means to urge the wheel toward the mandrel at all times so as to press the wire strand tightly thereagainst, a setting cam on the other side of the mandrel, and means to urge the said cam toward the mandrel to hold and guide a wound strand portion engaged thereby into a position to free it from said mandrel.

10. In an apparatus for winding a wire strand into a ribbon-like coil, a rotatable arbor including a body having pins extending from one face thereof to form a mandrel, a feed wheel on one

side of said mandrel to guide the wire strand onto said mandrel during rotation, means to urge the wheel toward the mandrel at all times so as to press the wire strand tightly thereagainst, a setting cam on the other side of the mandrel, means to urge the said cam toward the mandrel to hold and guide a wound strand portion engaged thereby into a position to free it from said mandrel, and set it ahead of its spring-back point.

10 ALLEN BENJAMIN.
